UNITED STATES PATENT OFFICE.

CLAUDE H. FRESEE, OF LOS ANGELES, CALIFORNIA.

FUMIGATOR.

1,162,690.

Specification of Letters Patent. Patented Nov. 30, 1915.

Application filed November 16, 1914. Serial No. 872,399.

To all whom it may concern:

Be it known that I, CLAUDE H. FRESEE, a citizen of the United States, residing at Los Angeles, in the county of Los Angeles, State 5 of California, have invented new and useful Improvements in Fumigators, of which the following is a specification.

This invention relates to a fumigator, and particularly pertains to a container for disinfectants.

It is the object of this invention to provide a disinfectant container which is particularly adapted for use in wardrobes, trunks and the like, as a protection against moths 15 and other insects, and which is so constructed that it may be suspended or laid in any desired location without danger of surrounding materials being injured by contact with the container and in which the parts of 20 the structure are so formed and arranged as to prevent leakage of the disinfectant material.

Another object is to provide a disinfectant container of annular formation adapted to 25 receive an absorptive material saturated with a volatile liquid in which the vapors from said liquid are emitted from the inner annular wall of the container and in which the escape of the vapors from the container can 30 be inhibited by introducing a closure member into the central opening of the container.

The invention is illustrated in the accompanying drawing, in which:

Figure 1 is a perspective view of the disinfectant container. Fig. 2 is a vertical section of same as seen on the line 2-2 of Fig. 1.

More specifically, 5 indicates the bottom member of the container which consists of a 40 sheet metal ring 6 having an upturned flange 7 on its outer edge and an upturned flange 8 on its inner edge; the flange 8 extending to a height approximately half that of the flange 7. The top portion of the container 45 comprises a ring 9 formed of sheet metal having a downturned flange 10 on its outer edge adapted to engage the upturned flange 7. The ring 9 is formed with a downturned flange 11 on its inner edge which terminates

a short distance from the upper edge of the 50 flange 8 to form an annular slot 12. The space incased by the rings 6 and 9 and the flanges thereon is filled with a suitable absorptive material 13 saturated with any desired disinfecting or deodorizing solution, 55 the vapors of which are emitted through the annular slot 12.

In the application of the invention, the container thus formed and charged may be placed in any desired location and position; 60 it being adapted to be suspended from any suitable support engaged by the central opening of the container or it may lie flat or be arranged in any position wherever it is desired to use same.

As a means for closing the slot 12 to prevent the escape of the vapors a cork or other suitable stopper 14 is introduced within the space encompassed by the annular flanges 8 and 11 as particularly shown in Fig. 2; the 70 stopper or closure 14 effectively sealing the slot 12.

What I claim is:

1. A disinfectant container, comprising an annular member having a chamber therein 75 adapted to receive an absorptive material saturated with a disinfecting solution having a slot on its inner peripheral wall to permit the escape of vapors.

2. A disinfectant container, comprising an 80 annular member formed with an internal chamber having a slot on its inner annular wall communicating with said chamber, and an absorptive material saturated with a disinfecting solution arranged within the 85 chamber.

3. A fumigator, comprising a pair of spaced rings having engaging annular flanges on their outer walls and formed with flanges on their inner edges toward each 90 other with their adjacent edges spaced apart to form a slot, and an absorptive material saturated with a disinfecting solution arranged between said rings.

4. A fumigator, comprising a pair of 95 spaced rings having engaging annular flanges on their outer walls and formed with flanges on their inner edges toward each

other with their adjacent edges spaced apart to form a slot, an absorptive material saturated with a disinfecting solution arranged between said rings, and a stopper adapted to be inserted in the space encircled by the inner flanges on said rings to seal the slot and prevent the emission of the fumes from the container.

Copies of this patent may be obtained for five cents each, by addressing the "Commissioner of Patents, Washington, D. C."

In witness that I claim the foregoing I have hereunto subscribed my name this 24th day of October, 1914.

CLAUDE H. FREESE.
